UNITED STATES PATENT OFFICE.

SAMUEL H. TACY, OF ELKINS PARK, PENNSYLVANIA, ASSIGNOR TO PRE-HEATED AIR COMPANY, OF PHILADELPHIA, PENNSYLVANIA, A CORPORATION OF DELAWARE.

PREHEATER.

1,153,273.

Specification of Letters Patent. Patented Sept. 14, 1915.

Application filed February 16, 1912. Serial No. 678,077.

To all whom it may concern:

Be it known that I, SAMUEL H. TACY, a citizen of the United States, and a resident of Elkins Park, Pennsylvania, have invented 5 a certain new and useful Preheater, of which the following is a specification.

My invention relates to pre-heaters intended to be secured in operative position within a furnace and which I prefer to 10 mount upon the furnace door to swing positively therewith.

The purpose of my invention is to provide a series of connecting, desirably straight, passages in such a pre-heater in a 15 construction having as great an extent of surface for heating as possible at the end toward the fire, and to distribute the air therefrom, preferably through a number of openings at an angle to each other and above 20 the fire.

A further purpose of my invention is to place as much of the pre-heater close to the fire as possible in a pre-heater having end, as opposed to side air inlet, and to secure 25 in this construction successively increased areas of cross section from the inlet to the outlet openings.

Further purposes of my invention will appear in the specification and claims 30 hereof.

I have preferred to illustrate my invention by one form thereof which has proved practical and efficient and which at the same time well illustrates the theory of my invention.

Figure 1 is a vertical section of a permissible furnace door and alley construction showing the preferred form of my invention in position. Fig. 2 is a vertical central longitudinal section of the form of pre-heater shown in Fig. 1. Fig. 3 is a top plan view, partly in section, of the structure of Fig. 2 without the top plate. Fig. 4 is a side elevation of a modified form of my invention.

Similar numerals of reference indicate like parts in the specification.

Any suitable furnace door such as 1 may be conveniently used as a mount for my pre-heater, and in the illustration, I have selected the boss 2, apertured to receive air inlet pipe 3, supporting the pre-heater through the boss or lug 4 upon the latter, as a convenient means of attaching my invention to the door, whereby the pre-heater is

preferably rigidly supported to swing with the door by means of its air inlet pipe.

The lower plate 5 of my pre-heater preferably lies in a horizontal position and is shown as carrying the partition portions and side walls in Figs. 2 and 3. The top plate 6 is shown to be secured to the bottom portion of the pre-heater by any suitable means 7, so as to engage the outer edges of the partitions and side walls, making the spaces 60 between the partitions effective as passages. These spaces between the side walls are shown as communicating and arranged in such order that the relatively cool inlet air passes first through the passage 8 against the outside wall 9, thence, in reverse direction, through passage 10, and, in successively reversed directions, through passages 11 and 12 respectively. All of the passages 65 so far indicated are preferably parallel and 70 at an angle to the group of passages upon the opposite side of the pre-heater, so that one set of passages shall be parallel to the outer side wall 9, while the other set of passages 75 parallel the outer side wall 13. The latter set of passages, in which the air moves in successively reversed directions is indicated at 14, 15 and 16. The air from the 80 passage 12 enters passage 14, and that from passage 16 is conducted through the transverse passage 17 and passage 18 into the end space 19, whence it is discharged, preferably at a plurality of angles, through the end apertures 20. It will thus be evident that 85 the air is subjected to a greater heat relatively when first admitted and just prior to its delivery to the furnace than during its intermediate travel, notwithstanding that the air in each passage receives substantially 90 the same heating effect from the top and bottom plates.

The tapered shape of my pre-heater, with the wider end toward the fire, gives the greatest width at that part of the pre-heater which is nearest to the fire, to considerable 95 advantage in heating the same.

In the form shown in Fig. 4 the pre-heater 100 may be held at an angle to the axis of the alley by pipe 3', and the end is provided with an enlargement.

It will be evident that the successively reversed directions of air flow are quite desirable in any form of heater other than circular, and that the form shown possesses considerable advantage in efficiency by rea- 110

son of the construction whereby this is accomplished.

It will be evident that the maintenance of substantial parallelism between the passages 5 and the nearer side walls causes substantial uniformity of resistance to flow and, consequently, of flow, relatively free from cross air currents.

I prefer to make each of the passages in 10 the direction of flow from the air inlet to the outlet slightly wider than the preceding passage, to provide for the increase of air volume with increased temperature, and have succeeded in effecting this in a balanced 15 form of tapered pre-heater without sacrifice of efficiency in the form illustrated.

Having thus described my invention, what I claim as new and desire to secure by Letters Patent is:

20 1. In a device of the character stated, a furnace door and a pre-heater mounted thereon of tapered external shape, having an inlet air connection, outlet air apertures and longitudinal air passages alternately reversing in direction of air travel and parallel to the nearer tapered walls of the heater.

25 2. In a device of the character stated, a pre-heater having tapered side walls, an inlet connection, outlet apertures and communicating passages of successively increased cross section from the inlet to the discharge opening, said passages being substantially parallel each to the nearer side wall alternating in direction, those at the center diverging to provide for the substantial parallelism with different side walls.

30 3. In a device of the character stated, an inlet air connection, a tapered pre-heater, fed therefrom, of approximately rectangular

transverse section, comprising communicating passages alternately reversed in direction of air travel and parallel to the nearer tapered walls and a chamber at the larger end provided with discharge apertures at variant angles.

4. In a device of the character stated, a tapered pre-heater of approximately rectangular transverse section having the relatively tapered outside walls generally longitudinally disposed, the pre-heater containing passages alternating in direction of air travel in adjoining passages, having the passages on one side, connected with an inlet opening at the rear of the pre-heater, substantially parallel with one of the relatively tapered walls and communicating with passages substantially parallel with the other relatively tapered wall, which latter passages are in communication with outlet openings at the front of the pre-heater.

5. In a device of the character stated, a pre-heater adapted for attachment to a furnace door, of substantially rectangular cross section and having two walls relatively tapered, the walls converging toward the 65 door, an inlet connection therefor, passages adjoining one of said tapered walls substantially parallel with it and passages adjoining the other wall substantially parallel with said second tapered wall, said passages 70 communicating at the middle, and outlet openings at the larger front end of the pre-heater.

SAMUEL H. TACY.
